UNITED STATES PATENT OFFICE.

WILLIAM SULLIVAN, OF HOT SPRINGS, ARKANSAS.

MECHANICAL MOVEMENT.

No. 894,861.

Specification of Letters Patent.

Patented Aug. 4, 1908.

Application filed July 16, 1907. Serial No. 383,982.

To all whom it may concern:

Be it known that I, WILLIAM SULLIVAN, a citizen of the United States, and a resident of Hot Springs, in the county of Garland and State of Arkansas, have invented a new and Improved Mechanical Movement, of which the following is a full, clear, and exact description.

The object of the invention is to provide a new and improved mechanical movement for converting reciprocating motion into a rotary motion in a very simple and effective manner.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a side elevation of the improvement; Fig. 2 is a plan view of the same, and Fig. 3 is a transverse section of the same on the line 3—3 of Fig. 1.

On a suitably constructed frame A, is mounted to reciprocate the cross head B, provided at its ends with handles B', adapted to be taken hold of by the operator for imparting a reciprocating motion to the cross head B. On the cross head B are mounted to swing two sets of pawls C and C', adapted to engage a ratchet wheel D, at diametrically opposite points, each set of pawls C, C' being arranged in a longitudinal row so as to successively engage and turn the ratchet wheel D. The pawls as shown are each formed of parallel and spaced rods or bars connected at their ends by plates. The ratchet wheel D is secured on a shaft E, journaled in suitable bearings mounted on the main frame A, and on the said shaft E is secured a pulley F, for transmitting the rotary motion of the device to other machinery to be driven.

Each of the pawls C has a limited swinging motion on the cross head B, and for this purpose each pawl extends through elongated slots B², formed in the sides of the cross head B. The sets of pawls C, C' are respectively pressed on by springs G, G' to hold the pawls in proper relation relative to the teeth of the ratchet wheel D, to turn the latter on reciprocating the cross head B. Now when the cross head B is caused to slide in the direc-

tion of the arrow a', then the upper pawls C successively engage the successive teeth of the ratchet wheel D, to turn the latter in the direction of the arrow b'. When the cross head B has reached the end of its stroke it is caused to slide backward, that is, in the inverse direction of the arrow a', and in doing so the pawls C' become active, that is successively engage successive teeth of the ratchet wheel D to further rotate the ratchet wheel in the direction of the arrow b'. During the forward sliding of the cross head B in the direction of the arrow a', the pawls C are active, as above described, while the pawls C' glide over the teeth of the ratchet wheel D, and when the cross head B is on the return stroke in the inverse direction of the arrow a', then the pawls C' are active, as above mentioned, while the pawls C glide over the teeth of the ratchet wheel D. Thus by the arrangement described a continuous rotary motion is given to the ratchet wheel D, the shaft E and the pulley F, on reciprocating the cross head B, as above explained.

The mechanical movement shown and described is very simple and durable in construction, composed of comparatively few parts, and not liable easily to get out of order.

Having thus described my invention, I claim as new and desire to secure by Letters Patent:

1. A mechanical movement comprising a frame, a ratchet wheel mounted in the frame, a cross head mounted to reciprocate in the frame and having oppositely arranged pairs of spaced members provided with slots, and a plurality of pawls pivoted to each pair of members of the cross head and adapted to engage the ratchet wheel at diametrically opposite points, each pawl consisting of spaced rods connected by plates, one rod forming the pivot and the other the pawl proper and working in the slots of the members of the cross head, and springs for holding the pawls in proper position.

2. A mechanical movement comprising a frame, a ratchet wheel mounted in the frame, a cross head mounted to reciprocate in the frame and having oppositely arranged pairs of spaced members each provided with transverse slots, and a plurality of pivoted and spring pressed pawls carried by each pair of members of the cross head and having their free ends working in the slots of the said members.

100

105

110

3. A mechanical movement, comprising a ratchet wheel, mounted to turn, a reciprocating cross head having transverse slots, sets of pawls for alternately engaging the ratchet wheel at diametrically opposite points to impart a continuous rotary motion to the wheel, the said pawls being pivoted to the cross head adjacent to the slots and having their free ends extending through the said

slots, and springs on the cross head and 10 pressing the said pawls.

In testimony whereof I have signed my name to this specification in the presence of two subscribing witnesses.

WILLIAM SULLIVAN.
